UNITED STATES PATENT OFFICE.

WILLIAM MANN, OF BAYONNE, NEW JERSEY.

MAIL-SEPARATING DEVICE FOR PIGEONHOLES.

1,220,525.

Specification of Letters Patent. Patented Mar. 27, 1917.

Application filed July 21, 1916. Serial No. 110,550.

To all whom it may concern:

Be it known that I, WILLIAM MANN, a citizen of the United States, residing at Bayonne, in the county of Hudson, State 5 of New Jersey, have invented a new and useful Mail-Separating Device for Pigeon-holes; and I do hereby declare the following to be a full, clear, and exact description of the invention, such as will enable 10 others skilled in the art to which it appertains to make and use the same.

This invention relates to an improved mail separating device for pigeon holes of a letter carrier's desk.

15 In the postal service of the Post Office Department, there are different classes of mail matter, and to promptly and accurately deliver the mail, the same is assorted, and in this connection a series of pigeon holes is used, in any one of which one class of mail matter is arranged, and in another another class is arranged and so on throughout the series of holes, and then the matter is subsequently removed and tied together 20 in different bundles. Very often the mail matter that is arranged in each hole or division is sub-assorted or sub-divided, and the aim of this invention is to provide means whereby the mail matter in each hole may 25 be sub-divided or sub-assorted.

At the present time there is employed a very crude sub-dividing device, which consists of a flat elongated board having wire arms extending into the pigeon holes for 30 sub-dividing the same, and which device has been found impractical, because the wire arms are continually becoming detached. Moreover, this kind of device when 35 removed is in the way around the letter carrier's desk, and very frequently becomes lost or misplaced.

Another aim of this invention is to provide a permanently attached sub-dividing device, and when the sub-dividing members 40 are not needed, they may be thrown under the horizontal divisional members or partitions.

A further object of the invention is to improve and render more practical the mail 45 separating device for pigeon holes, set forth, illustrated and claimed in the co-pending application of William Mann, filed May 3, 1916, Serial Number 95,207.

To improve and render more practical 50 said mail separating device in the aforesaid application, it is the aim to provide a

member in the rear of each pigeon hole, to limit the mail matter in its insertion, that is when the sub-dividing devices are used, and which member may be thrown backwardly out of position, when the sub-dividing devices are not used. 60

A further aim of the invention is to provide means for actuating the limiting or abutment members and the separating devices simultaneously, and a further aim of the invention is to employ said members as means for throwing the mail matter partially forward so that the mail matter may 65 be easily grasped. 70

In practical fields, the details of construction may necessitate alterations falling within the scope of what is claimed. 75

The invention comprises further features and combination of parts, as hereinafter set forth, shown in the drawings, and claimed. 80

In the drawings:

Figure 1 is a view in front elevation of a letter carrier's pigeon hole cabinet, showing the mail separating or sub-dividing devices, 85 as applied thereto, and the mail limiting members.

Fig. 2 is an end view of the cabinet, showing the means for actuating said separating or subdividing devices and said mail matter limiting members. 85

Fig. 3 is a sectional view on line 3-3 of Fig. 1.

Fig. 4 is a sectional view on line 4-4 of Fig. 1. 90

Fig. 5 is a perspective view of the mail separating or sub-dividing device and one of the limiting members, showing the means for actuating both at the same time.

Referring more especially to the drawings, 1 designates a letter carrier's pigeon hole cabinet as a whole, which consists of the body casing 2, which is divided to form the pigeon holes 3, by means of the horizontal and vertical partitions 4 and 5. 100 Mounted in bearings of the end walls of the body casing adjacent the forward edge of the horizontal partition 4 is a shaft 6, the bearings of which are designated by the numeral 7, some of which are secured to the 105 vertical partitions. Also mounted in bearings of the end walls of the cabinet and the partition walls of the uppermost pigeon holes is a horizontal shaft 8. The shaft 6 is provided with a crank 9 at one end, and 110 a gear 10. One end of the shaft 8 has a gear 11.

The shaft 6 is provided with a plurality of series of angular arms 12 (which are similar to those in the aforesaid application) designed to assume vertical positions in the forward portions of the uppermost pigeon holes 3, that is, when said arms are used to divide the pigeon holes. There is a series of arms for each pigeon hole. Carried by the shaft 8 is a plurality of rectangular members 13 constructed of heavy wire, there being one for the rear of each uppermost pigeon hole. When the arms 12 are used for sub-dividing the pigeon holes said members 13 lie adjacent the bottoms of said pigeon holes, thereby limiting the mail matter in its insertion in said pigeon holes, particularly when the mail matter is shorter than the depths of said pigeon holes, so that the arms 12 will readily hold the mail matter sub-divided in the several pigeon holes. Mounted in the guide bearings 14 is a slide bar 15, adjacent one end of the cabinet. The forward end of the bar on its lower edge is provided with rack teeth 16, which mesh with the teeth of the gear 10. The upper edge of the bar 15 at its rear end is provided with rack teeth 17, which mesh with the teeth of the gear 11, which is larger in diameter than the gear 10, so that when the bar 15 is reciprocated in one direction or the other, the shaft 8 will rotate substantially a quarter revolution to substantially a three quarter revolution of the shaft 6, whereby when the members 13 are oscillated rearwardly to a vertical position, the arms 12 will be thrown under and adjacent the horizontal partition 4. By this arrangement of the gears and the rack bar, a partial movement of the bar 15 rearwardly, that is when the members 13 are assuming vertical positions, will oscillate said members 13 slightly forwardly, so that the mail matter is shoved forwardly to be grasped, before the arms 12 reach their vertical positions.

45 The invention having been set forth, what is claimed as new and useful is:—

1. In a sub-dividing device for a row of

pigeon holes, the combination of a cabinet having a row of pigeon holes and a shaft in bearings on the cabinet adjacent the bottoms of the pigeon holes, of a plurality of series of arms carried by the shaft one series for each pigeon hole for sub-dividing the mail matter inserted therein, a second shaft mounted in bearings on the cabinet at the rear of the pigeon holes and carrying a plurality of mail limiting members, one for each pigeon hole, and means geared to said shafts for rocking said shafts in opposite directions, whereby as the arms are thrown down and under the pigeon holes, the limiting members are thrown upwardly to vertical positions.

2. In a subdividing device for a row of pigeon holes, the combination of a cabinet having a row of pigeon holes and a shaft in bearings on the cabinet adjacent the bottoms of the pigeon holes, of a plurality of series of arms carried by the shaft one series for each pigeon hole for sub-dividing the mail matter inserted therein, a second shaft mounted in bearings on the cabinet at the rear of the pigeon holes and carrying a plurality of mail limiting members, one for each pigeon hole, and means geared to said shafts for rocking said shafts in opposite directions, whereby as the arms are thrown down and under the pigeon holes, the limiting members are thrown upwardly to vertical positions, said geared means comprising gears of different diameters, the gear of larger diameter on the second shaft, and the gear of smaller diameter on the first shaft, guide bearings on one end of the cabinet, and a rack mounted in the guide bearings to mesh with the gears for rocking the shafts simultaneously.

In testimony whereof I have signed my name to this specification in the presence of two subscribing witnesses.

WILLIAM MANN.
